UNITED STATES PATENT OFFICE.

THOMAS M. BELL, OF PHILADELPHIA, PENNSYLVANIA, ASSIGNOR TO THE
CHARLES SCOTT SPRING COMPANY, OF SAME PLACE.

DESIGN FOR A PLATE FOR CAR-SPRINGS.

SPECIFICATION forming part of Design No. 18,838, dated January 8, 1889.

Application filed December 3, 1888. Serial No. 292,542. Term of patent 14 years.

To all whom it may concern:

Be it known that I, THOMAS M. BELL, a citizen of the United States, and a resident of Philadelphia, Pennsylvania, have invented 5 a new and original Design for a Plate for Car-Springs, of which the following is a specification.

My design for a plate for car-springs is fully shown in the accompanying drawings, in 10 which—

Figure 1 is a perspective view of the plate, and Fig. 2 is a plan view of the same.

The outline of the plate is formed by three segments, A, A', and B, the centers of the 15 segments A, A' occupying the same transverse plane, x, while the center of the segment B is in a plane, y, passing at right angles through the plane x midway between the

centers of the segments A A'. The segment B is of considerably greater radius than the 20 segments A A', and this is an essential feature of the design.

Minor or unimportant features are the flange d, the projecting spurs or teats b, and the depressions a a, the latter being located 25 centrally in respect to the segments A A'.

I claim—

The design for a plate for car-springs, substantially as described and shown.

In testimony whereof I have signed my name 30 to this specification in the presence of two subscribing witnesses,

THOMAS M. BELL.

Witnesses:

WILLIAM D. CONNER,
HARRY SMITH.
